CHRISTIAN G. LEHMANN, OF DETROIT, MICHIGAN.

COIN-CONTROLLED LOCK.

1,105,980.

Specification of Letters Patent.

Patented Aug. 4, 1914.

Application filed April 28, 1913. Serial No. 764,056.

To all whom it may concern:

Be it known that I, CHRISTIAN G. LEHMANN, a subject of the Emperor of Germany, residing at Detroit, in the county of Wayne and State of Michigan, have invented certain new and useful Improvements in Coin-Controlled Locks, of which the following is a specification, reference being had therein to the accompanying drawings.

10 This invention relates to improvements in coin controlled locks and its object is to provide means whereby a key for operating the lock is held against turning or removal from the lock, said means being adapted to be actuated by a coin to release the key and being so arranged that when the key is again inserted in the lock it will be held against removal until the mechanism is actuated by another coin.

20 To this end the invention consists in the matter hereinafter set forth and more particularly pointed out in the appended claims, reference being had to the accompanying drawing, in which,

25 Figure 1, is a side elevation of coin controlled mechanism embodying the invention with parts broken away to show the construction; Fig. 2, is a plan view of the same with the surrounding casing and parts 30 shown in section; Fig. 3, is a sectional detail of the coin chute; and Fig. 4, is a transverse sectional detail of a portion of the mechanism showing a key in side elevation.

A lock and its coin controlled mechanism 35 is shown as applied to a door A, the lock B which may be of any desired form and construction, having a bolt C to engage a socket D in the edge of a door casing E which surrounds the door. The mechanism 40 is especially designed for application to the doors of cabinets or lockers which are placed in public places for holding, temporarily, the outer clothing of guests, the idea being to obviate the necessity for checking the garments with the consequent expense of employing an attendant and the resulting loss and confusion in handling the clothing. The device may however be applied to a lock for other devices and may be arranged in 45 any suitable manner.

The lock B is shown as inclosed within a suitable casing 1, which may be let into the door A or otherwise secured thereto in any suitable manner. This casing forms a closure 50 for the coin controlled mechanism and is provided with a coin chute 2 which opens

through the top of the casing to receive a coin and discharges into the bottom of the casing. The outer side of the casing is also formed with an opening to receive a key 3 60 and a suitable upwardly extending guide 4 is provided on the casing to form a support and guide for the key when the same is inserted therethrough to engage the lock. The inner end of the key is formed in the usual 65 manner to engage and operate the mechanism of the lock and adjacent to this end portion or intermediate the ends of the key, the same is formed with notches 6 and 7 in a laterally extending portion or flange of 70 the key. Pivots supported intermediate its ends upon a pivot rod 8 extending across the casing is a latch bar 9 formed with a notch 10 near one end to engage the notch 6 in the middle portion of the key and prevent its removal from the casing. The opposite end of the latch bar 9 is provided with a finger 11 which projects through a longitudinal slot 12 in the coin chute 2, and the pivot 8 is so placed that the latch bar is normally held by gravity with its notched end 75 10 in engagement with the key said notch being formed with a straight side adjacent to the end of the bar, forming a shoulder to prevent the key from being turned in 80 that direction and the opposite side of the notch being inclined to permit the key to turn freely toward the pivot of the latch bar.

To engage the side of the key which is 85 toward the pivot 8 of the latch bar 9 and normally prevent said key from turning in that direction, a gravity dog 13 is pivoted intermediate its end upon a transverse pivot pin 14 and is beveled at one end, forming a 90 point 15 to engage a notch in the side of the key and prevent the key from turning toward the dog. The opposite end of the dog is provided with a tail piece 15 which extends through the slot 12 in the coin chute 100 at a considerable distance below the finger 11. A stop 16 on the casing engages the dog 13 and prevents the same from turning into the path of the key when the same is inserted in the casing. Secured to one side of 105 the casing and extending part way across the same adjacent to one side of the chute, is a spring finger 17 adapted, as shown in Fig. 3, to be engaged by the finger 11 when the same is depressed by a coin placed in 110 the chute and falling upon the finger. The weight of such a coin is sufficient to overbal-

ance the latch 9 and lift its notched end out of engagement with the key. The weight of the coin is also sufficient to hold the latch bar so turned with its finger 11 resting upon the spring 17. The key is therefore released by the turning of the latch bar when a coin is placed in the chute and said key may be turned to the left to unlock the door.

A rocker bar 18 is pivoted at 19 within the casing with one end extending over the upper edge of the key, and pivotally attached to this rocker bar at one side thereof, is a dog 20 adapted to engage the notch 7 in the key when said key is in engagement with the lock. This dog 20 is arranged to turn freely away from its bar and thus permit the key to be drawn out when the latch bar 9 is actuated by a coin, but when the key is again inserted, the end of the dog 20 engages an inclined surface on the key, and as the dog is prevented from swinging toward the bar by its engagement therewith, said bar will be lifted when the key is inserted in the lock. An extended end or finger 21 on the bar 18 projects beneath the latch bar 9 adjacent to the pivot 8 thereof and thus when the key is inserted and the bar 18 swung upwardly by the engagement of the key with the dog, the latch bar 9 will be turned upon its pivot sufficiently to withdraw the finger 11 from across the slot in the coin chute and permit the coin resting therein to pass down the chute and fall upon the tail piece 15 of the gravity dog 13. The falling of the coin upon the tail piece turns the dog upon its pivot and swings its pointed end away from the side of the key, thus permitting the key to be turned to the right, the weight of the coin holding the dog so turned with the tail piece in engagement with and yieldingly supported by a spring finger 22 secured at one end to the casing and extending transversely thereof adjacent to one side of the coin chute in a manner similar to the finger 17. When the latch bar 9 is turned as described by the insertion of the key, it will fall back to normal position as soon as the dog 20 drops into the notch 7 of the key, said spring finger 17 assisting to throw the notched end of the latch bar into engagement with the notch 6 of the key.

Pivotally supported upon a transverse rod 23 is a swinging arm 24 having an extended end portion 25 resting upon the spring 22. This arm is also provided with an upwardly extended arm 26 positioned adjacent to the side of the key 4 which is engaged by the dog 13. When the arm 24 is normally held by the spring 22, its laterally extending arm 28 projects upwardly close to the side of the key, and when the dog 13 has been turned out of engagement with said side of the key by a coin passing down the coin chute, the key may be turned to the right to operate

the lock and when so turned, said key will engage the arm 26 and swing the arm 24 downwardly against the action of the spring finger 22. The weight of the coin upon the tail piece 15 of the dog 13 will turn the dog 70 when the spring is so depressed by the arm 24 and said tail piece 15 will thus be withdrawn from across the slot of the coin chute, permitting the coin to pass the end therefor and drop out of the open lower end of the 75 chute. The coin is thus released and falls into the bottom of the casing 1, and as the key turns back to normal position, the swinging arm 24 will be turned upwardly by the spring 22 with the arm 26 adjacent 80 to the side of the key.

Where this device is applied to lockers or similar devices, a customer places a coin in the chute. This operates the latch bar 9 and releases the key so that it may be turned 85 to unlock the door of the locker. He may then place his clothing in the locker, close the door and remove the key, taking it with him. When he returns, the insertion of the key raises the rocker bar 18 which in turn 90 further actuates the latch bar 9 and allows the coin to pass the end of the finger 11 and drop down the chute into engagement with the tail piece of the dog 13. This moves the dog 13 out of engagement with the side 95 of the key, at the same time permitting the latch bar to fall into engagement with the notch 6 of the key, but owing to the shape of the notch in the key, said key may be turned toward the right to unlock the door. 100 He may then remove his clothing from the locker and close the door but in unlocking the door he has turned the key to the right and in so doing operated the swinging arm 105 13 and the escape of the coin into the bottom of the casing. The fall of the latch bar back into engagement with the key after the coin has passed the finger 11, locks the key 110 within the casing and prevents the customer from again removing the key without inserting another coin.

Obviously changes may be made in the construction and arrangement of parts without departing from the spirit of my invention and I do not therefore limit myself to the particular form or arrangement shown.

Having thus fully described my invention, what I claim is:

1. The combination of a casing, a lock in 120 said casing, a key for operating the lock, a coin chute, and means independently engaging opposite sides of the key to prevent the turning thereof and its removal from engagement with the lock, said means being 125 adapted to be successively actuated by a coin passing down the coin chute to release the key.

2. The combination of a casing, a lock in 130 said casing, a bolt forming part of said lock,

a coin chute, a key adapted to operate the lock, a member within the casing to lock a key against removal from the lock and against turning and adapted to support a coin placed in said chute, said member being adapted to be operated by a coin contacting therewith in the coin chute to release the key, and means independent of said bolt operated by the insertion of the key in the lock for releasing the coin.

3. The combination of a casing, a lock in said casing, a bolt forming part of said lock, a key for operating the bolt of said lock, a key engaging member to prevent the longitudinal and rotary movement of the key and adapted to be moved and held out of engagement with the key by a coin deposited on said member, and a second member independent of said bolt and actuated by the insertion of the key in the lock for actuating the member for engaging the key, to release the coin from engagement therewith and permit the reengagement of said key engaging member with the key.

4. The combination of a casing, a lock in the casing, a bolt forming part of said lock, a key for operating the bolt of the lock provided with a notch, a latch bar to engage in the notch and provided with a notch to receive the key, and adapted to be directly operated by a coin and held by said coin resting on said bar out of engagement with the key, and means actuated independent of said bolt by the insertion of the key in the lock to release the coin.

5. The combination of a casing, a lock in said casing, a bolt forming part of said lock, a key for operating the bolt of the lock, a latch bar to engage the key and prevent its withdrawal from the lock and the turning thereof in one direction to actuate the bolt, a dog to prevent the turning of the key in an opposite direction, means actuated by a coin for turning the latch bar to release the key and permit said key to be turned and withdrawn from engagement with the bolt, said means temporarily supporting the coin, and means actuated independent of said bolt by the insertion of the key in the lock to release the coin, said dog being arranged to be actuated by the coin when released to release the key and permit the same to be turned in a direction opposite to that in which it is held from turning by the latch bar.

6. The combination of a casing, a lock in said casing, a key for operating the lock, a pivoted latch bar to engage the key at one end and prevent longitudinal and turning movement thereof, a coin chute, a finger on the latch bar extending across the coin chute adapted to be engaged by and support a coin passing down the chute to turn the latch bar out of engagement with the key, a pivoted dog to engage the key and extending into

the path of the coin passing down the chute, and means for actuating the latch bar when the key is inserted in the lock to release the coin in the coin chute and permit the same to drop into engagement with the dog.

7. The combination of a casing, a lock in said casing, a bolt forming part of said lock, a key adapted to be inserted in the lock for operating the bolt of the lock, a coin chute, a pivoted latch bar to engage the key at one end, a finger on the latch bar extending across the coin chute and adapted to support a coin placed in said chute and be actuated thereby to turn the latch bar out of engagement with the key, a member actuated by the insertion of the key in the lock for turning the latch bar and moving its finger from across the chute, and means independent of said bolt actuated by the turning of the key for releasing the coin from the chute.

8. The combination of a casing, a lock in said casing, a key adapted to be inserted in the lock for operating the same, a coin chute, a latch bar to engage the key and adapted to be turned out of engagement with the key and held in a position to which it is turned by a coin passing down the chute and supported by said bar, a pivoted member adapted to engage the latch bar and release the coin, and a dog on the pivoted member adapted to be engaged by the key and to operate the pivoted member when the key is inserted in the lock.

9. The combination of a casing, a lock in the casing, a key for operating the lock having a notch, a pivoted latch bar having a notch in one end to engage the notch in the key, a finger on the opposite end of the latch bar, a coin chute across which the finger extends whereby said finger can support a coin in said chute, a spring stop for the finger of said latch bar into engagement with which it is turned by a coin passing down the chute and engaging the finger, a pivoted member adapted to engage and turn the latch bar against the action of said spring stop, a dog on said pivoted member to engage the key and adapted to turn to permit the removal of the key and to actuate said member when the key is inserted in the lock, and a pivoted member adapted to be turned by the turning of the key to release the coin.

10. The combination with a casing, a lock in said casing, and a key to engage the lock having notches in one side, of a coin chute having a longitudinal slot, a pivoted latch bar having a notch to engage one of the notches in the key and prevent longitudinal movement of the key and its turning in one direction, a finger on the opposite end of the latch bar extending through the slot in the coin chute and adapted to support a coin therein, a spring stop for the latch bar, a pivoted member adapted to be turned into engagement with the latch bar to turn said

bar against the action of said spring stop and release the coin held thereby, a dog pivotally attached to the pivoted member and adapted to engage one of the notches in the key, a gravity dog pivotally supported in the casing to engage one side of the key, said dog having an opposite end extending through the slot in the coin chute and adapted to support a coin and be actuated thereby,
10 a spring stop for said gravity dog, and means actuated by the turning of the key to depress the spring stop for the gravity dog, and release the coin held thereby.

11. In a coin controlled key lock, the com-

bination with a key, of means engaging one 15 side of the key and actuated by a coin to release said key and permit of rotation in one direction, and means engaging the opposite side of the key and actuated by the same coin to release said key whereby it can be rotated 20 in an opposite direction.

In testimony whereof I affix my signature in presence of two witnesses.
